UNITED STATES PATENT OFFICE.

GARLAND E. MARTIN, OF NORFOLK, VIRGINIA.

RAZOR-STROP.

986,190.

Specification of Letters Patent. Patented Mar. 7, 1911.

Application filed January 14, 1910. Serial No. 538,068.

To all whom it may concern:

Be it known that I, GARLAND E. MARTIN, a citizen of the United States, residing at Norfolk, in the county of Norfolk and State 5 of Virginia, have invented a new and useful Razor-Strop, of which the following is a specification.

This invention relates to razor strops.

The ordinary types of strops utilizing 10 flexible members designed to be held at one end by a supporting nail or the like and to be grasped at the other end by the hand of the operator, have been found objectionable because the side portions of the flexible members 15 tend to sag when the razor is pressed upon the device and, as a result, the edge of the razor is not rubbed uniformly throughout its length. Moreover it has been difficult to prevent the strop from buckling while 20 in use.

One of the objects of the present invention is to avoid the objections above enumerated and to provide the strop with a pliable filling or reinforce of wood, metal or other suitable material and which constitutes an efficient backing for the strop throughout its width, thus preventing buckling of the strop or sagging of the edge portions thereof.

Another object is to provide improved 30 means for connecting the parts of the strop and for attaching said strop to a supporting device.

With these and other objects in view the invention consists of certain novel details of 35 construction and combinations of parts hereinafter more fully described and pointed out in the claims.

In the accompanying drawings the preferred form of the invention has been shown. 40 In said drawings, Figure 1 is a perspective view of a strop embodying the present improvements, a portion of the sheathing of the reinforce being broken away. Fig. 2 is an enlarged section on line A—B Fig. 1.

45 Referring to the figures by characters of reference 1 and 2 designates spaced similar plates connected by an integral arched extension 3 in which is swiveled an eye 4 designed to engage a suitable supporting device. The plates 1 and 2 have a clamping bolt 5 extending through the centers thereof and the end of which is engaged by a thumb nut 6.

50 Projecting between the plates 1 and 2 are the two flexible members constituting the body portion of the strop, one of these mem-

bers being in the form of a leather strip 7 while the other member is in the form of a sheath 8 of canvas or the like, one end of the sheath extending between the plates 1 60 and 2 while the other end thereof is fastened to a tab 9 of leather or other suitable material and which constitutes a grip or handle. The adjoining end of the strip 7 may be shaped to correspond with the tab 9. 65

A pliable strip 10 of metal, wood, or any other suitable material is fitted tightly within the sheath and extends from the tab 9 to the plates 1 and 2, the opposed faces of this strip being flat and forming smooth 70 backing faces on which the working portions of the sheath rest. The strip 10 thus serves to reinforce the sheath and as it extends throughout the width thereof, it will be apparent that downward pressure of a razor 75 against the sheath will be resisted to the same extent throughout the width of the strop. The uniform sharpening of the razor edge is thus insured.

The particular means employed for attaching the members 7 and 8 together at their upper ends is deemed of importance because of its simplicity and durability and further because by swiveling the eye 4 therein the strop can be readily reversed so as to 85 bring either the member 7 or the member 8 uppermost.

By mounting the reinforce 10 within a sheath or tube, lateral displacement of the reinforce relative thereto is prevented and 90 there is no danger of the razor coming into contact with the reinforce as would be the case should such lateral displacement occur.

Various changes can of course be made 95 in the construction and arrangement of the parts without departing from the spirit or sacrificing any of the advantages of the invention as defined in the appended claims.

What is claimed is:—

1. A razor strop including a flat tubular sheath of flexible material and having parallel working faces, and a continuous flat flexible reinforcing strip concealed within the sheath and extending throughout the 105 width of the interior thereof, said strip constituting means for preventing sagging of the edge portions of the sheath when subjected to pressure.

2. A razor strop including clamping 110 plates, an arcuate connection integral therewith, a support engaging member swiveled

within the connection, and flexible members extending between and held together by the plates, one of said members including a flat tubular case, and a longitudinally extending flat flexible reinforcing strip formed in one piece and concealed within the sheath.

5 In testimony that I claim the foregoing as

my own, I have hereto affixed my signature in the presence of two witnesses.

GARLAND E. MARTIN.
